UNITED STATES PATENT OFFICE.

HENRY G. ROTH, OF MINNEAPOLIS, MINNESOTA.

DESIGN FOR A DISPLAY-FIXTURE FOR STORES.

SPECIFICATION forming part of Design No. 33,345, dated October 9, 1900.

Application filed July 30, 1900. Serial No. 25,352. Term of patent 14 years.

To all whom it may concern:

Be it known that I, HENRY G. ROTH, a citizen of the United States, residing at Minneapolis, Hennepin county, Minnesota, have invented and produced a new and original Design for a Display-Fixture for Stores, of which the following is a specification, reference being had to the accompanying drawing, forming part thereof.

10 In said drawing the single view is a perspective, partly in section, illustrating a display fixture for stores embodying my invention.

As therein shown, the leading or material features of my design are the columns *a*, the coving-plates *b*, and the relatively large and small crescent-shaped bodies *c* and *d*, arranged to form colonnades, appearing as supported by the said columns. The lower columns *a* are shown as rising from the counter *e*, while

20 the upper columns are shown as rising from

the upper of a series of shelves *f f' f²*. The cove-plates *b* are shown as curved upward and outward from a cornice or ledge *g*, which, as well as the shelves *f f' f²* and the counter *e*, is shown as extended from the room-wall *h*. 25

This design is especially intended for use in groceries and other stores for displaying canned and bottled goods.

Having thus described my invention, what I claim as new, and desire to secure by Letters 30 Patent of the United States, is as follows:

The design for a display-fixture for stores, substantially as herein shown and described.

In testimony whereof I affix my signature in the presence of two witnesses.

HENRY G. ROTH.

Witnesses:

A. L. MILLER,
T. A. MILLER.
